UNITED STATES PATENT OFFICE.

MAX MILLER, OF BROOKLYN, NEW YORK.

TOY KITCHEN.

SPECIFICATION forming part of Letters Patent No. 289,121, dated November 27, 1883.

Application filed October 20, 1883. (No model.)

To all whom it may concern:

Be it known that I, MAX MILLER, of Brooklyn, Kings county, and State of New York, have invented certain new and useful Improvements in Toy Kitchens, of which the following is a full, clear, and exact description.

The object of my invention is to provide certain new and useful improvements in toy kitchens, whereby the spilling and splashing of water, caused by the working of the toy pump usually attached to a toy kitchen, are prevented to a great extent.

The invention consists in the combination, with a toy kitchen, of a tank held removably to the side of the same, which tank is provided with a faucet.

Reference is to be had to the accompanying drawings, forming a part of this specification, in which similar letters of reference indicate corresponding parts in both the figures.

Figure 1 is a perspective view of a toy kitchen provided with my improvement. Fig. 2 is a longitudinal sectional elevation of one end of the same.

To the outer surface of one end or wall or piece, A, of a toy kitchen a band, B, is fastened, which forms a pocket for receiving a downwardly-projecting hook or loop, C, fastened to the upper part of the flat side of a small tank, D, adapted to fit against the side of the kitchen. The tank D is provided with a cover, E, and with a small faucet, F, for drawing water, at the bottom. A cup, G, is held by a chain, H, to the faucet or to the tank, and a hook, J, is secured on the side of the kitchen, on which hook the cup can be hung. If water is

to be drawn, all that is necessary is to press down the knob of the faucet, which faucet is self-closing. Water can thus be drawn without jarring and shaking the entire toy kitchen and throwing down the dishes, pans, &c., as frequently occurs in toy kitchens provided with a pump, and the splashing and spilling of water are avoided to a great extent.

If desired, the tank can be provided with upwardly-projecting wing L, having an aperture through which a pin or stud projecting from the outer surface of the side of the kitchen can be passed.

Having thus described my invention, I claim as new and desire to secure by Letters Patent—

1. The combination, with a toy kitchen, of a water-tank held removably to one side of the same, substantially as herein shown and described.

2. The combination, with a toy kitchen, of a tank held to the side of the same and provided with a faucet, substantially as herein shown and described.

3. The combination, with a toy kitchen, of the tank D, having a faucet, F, the cup G, the chain H, and the hook J, substantially as herein shown and described.

4. The combination, with a toy kitchen, of the band B, secured to the outer surface of one side, the tank D, and the downwardly-projecting hook or loop C, secured to the same, substantially as herein shown and described.

MAX MILLER.
